UNITED STATES PATENT OFFICE.

HENRY W. WACHTELHAUSEN, OF MERIDEN, CONNECTICUT, ASSIGNOR TO THE PARKER CLOCK COMPANY, OF MERIDEN, CONNECTICUT, A CORPORATION OF CONNECTICUT.

DESIGN FOR AN ALARM-CLOCK CASE.

44,946.

Specification for Design.

Patented Nov. 25, 1913.

Application filed July 16, 1913. Serial No. 779,403. Term of patent 7 years.

To all whom it may concern:

Be it known that I, HENRY W. WACHTELHAUSEN, a citizen of the United States, residing at Meriden, in the county of New Haven and State of Connecticut, have invented a new, original, and ornamental Design for an Alarm-Clock Case, of which the following is a specification, reference being had to the accompanying drawings, forming part thereof, and in which—

Figure 1 is a front elevation of an alarm clock case showing my new design, and, Fig. 2 is a side elevation of the same.

I claim:

The ornamental design for an alarm clock case as shown.

HENRY W. WACHTELHAUSEN.

Witnesses:

HEATH SUTHERLAND,
WM. J. WESSENBERG.
